UNITED STATES PATENT OFFICE.

BERT W. WILLIAMS, OF FARWELL, MICHIGAN, ASSIGNOR OF ONE-HALF TO VIOLA RITTER, OF CLARE, MICHIGAN.

SANDPAPERING-MACHINE.

1,195,428.

Specification of Letters Patent. Patented Aug. 22, 1916.

Application filed March 20, 1916. Serial No. 85,455.

To all whom it may concern:

Be it known that I, BERT W. WILLIAMS, a citizen of the United States, residing at Farwell, in the county of Clare and State of Michigan, have invented certain new and useful Improvements in Sandpapering-Machines, of which the following is a specification.

This invention has relation to certain new and useful improvements in sand papering machines and has for its primary object the provision of a floor sand papering machine which will be of simple construction and operation as well as highly efficient in use.

Another object of the invention resides in the provision of a floor sand papering machine which will be of such construction that it may be readily drawn along the floor or other surface to be sand papered, with the sand paper or smoothing member resiliently retained in engagement with the surface.

The invention has for a further object, the provision of a machine of this character in which the pressure block will be resiliently retained in engagement with the block carrying the sand paper or other smoothing member during reciprocation of the same over the surface across which the machine is being drawn.

A still further object of the invention resides in the provision of a machine of this character in which reciprocating movement may be imparted to the sand paper carrying block upon rotation of the supporting wheel of the body during movement of the complete device over the surface to be treated.

With the above and other objects in view this invention relates to the novel construction, combination and arrangement of co-operating elements as will be hereinafter more fully set forth and pointed out in the appended claims and shown in the drawings in which:

Figure 1 is a side elevation of the complete device, Fig. 2 is a top plan view, Fig. 3 is a longitudinal vertical section, Fig. 4 is a transverse section substantially on the plane of line 4—4 of Fig. 1, Fig. 5 is a detail longitudinal section on the plane of line 5—5 of Fig. 4, and, Fig. 6 is a detail trans-

verse section on the plane of line 6—6 of Fig. 4, Fig. 7 is a vertical transverse section through the body to show the operating means for the pitman arm.

Referring to the drawings in which similar reference characters designate corresponding parts throughout the several views, 1 designates the body, in the depending sides 2 of which are mounted the forward and rear bearing and supporting members 3 for the forward and rear axles 4 and 5 respectively. Upon the forward axle 4 are mounted the forward wheels 6 while the rear wheels 7 are mounted upon the rear axle 5. The wheels 6 and 7 are preferably positioned within the body 1, as shown in the drawings and provided with suitable tires 8 in order to prevent injury to the surface over which the device is to be drawn by means of the handle 9. The handle 9 is bifurcated and has its opposite portions pivoted to the sides 2 of the body 1 in a suitable manner, as shown at 10. The handle 9 is also provided with a removable extension 11 of suitable form. It will be evident that the removable handle extension 11 may be readily disconnected from the body of the handle 9 when the device is not in use.

Mounted upon the forward shaft 5 is a large gear 12 which meshes with a smaller gear 13 carried upon the crank shaft 14, upon the crank portion 15 of which is mounted one end of the pitman arm 16 which has an offset portion 17 to avoid the rear shaft 5. It will be understood that the crank portion 14 is mounted in one side 2 of the body 1. The rear end of the pitman arm 16 is pivoted to an upstanding ear 18 of a bracket plate 19 which in turn is secured to the upper face of the sandpaper carrying block 20, about the center of the same. It will therefore be seen that as the body 1 is drawn along the surface, the sand paper carrying block 20 will follow the same and reciprocate upon the surface, owing to the reciprocating movement imparted to the same by means of the pitman arm 16.

The sand paper carrying block 20 has a sheet of sand paper 21 or other suitable smoothing material secured upon its lower face with the forward and rear edges bent

- back over the forward and rear edges of the block 20 and over the transverse grooves 22 formed in the upper face of said block 20. The opposite edges of the sheet 21 are held 5 in proper position by means of the transverse clamping strips 23 which have ribs 24 formed upon their under faces for forcing the sheet into the transverse grooves 22. It will be understood that suitable clamp nuts 10 25 are threaded upon the bolts 26 projecting upwardly from the block 20 and extending through suitable openings provided for the same in the strips 23. It will therefore be seen that when the thumb nuts 25 are threaded 15 downwardly upon the bolts 26, the transverse strips 23 will be securely clamped upon the strip 21. It will be understood that any suitable material may be substituted for the sand paper sheet 21.
- 20 In order that the block 20 may be held in proper position with respect to the body 1 I have provided a pair of guide arms 27 which are carried by the sides 2 of the body 1, near the rear end of the same, the offset rear ends 25 28 of the guide arms 27 being slidably engaged in the guide sleeve 29 mounted upon the block 20, adjacent the sides of the same, as clearly shown in Fig. 2. As will be seen by referring to Fig. 5, each offset end 28 of 30 the guide arms 27 is provided with an elongated longitudinal slot 30, within which is engaged the transverse pin 31 positioned in the rear end of the sleeve 29 in which the end 28 reciprocates.
- 35 In order that the sand paper sheet 21 may be resiliently retained in engagement with the surface to be smoothed or sand papered, I provide a pair of pressure rollers 32 mounted in the bifurcated brackets 33 which 40 are in turn mounted upon the pins 34 which project through the opposite end of the cross bar 35 and also through the body portion 36 of said brackets 33. It will be seen that the rollers 32 press upon the upper face of the block 20, owing to the pressure exerted upon the upper face of the cross bar 35 by the arcuate spring 37. The arcuate spring 37 has its opposite ends 38 bifurcated and engaged upon the suspending bolts 39 which 45 depend from the cross member 40 and project through the cross bar 35, a suitable distance from the opposite ends of the same, the nuts 41 being threaded upon the lower ends of said suspending bolts 39. The arcuate spring 37 has a socket member 42 mounted centrally upon its upper face to receive one end of the set screw 43 which is threaded through the center of the cross member 40 and the end of the supporting arm 44, upon which said cross member 40 is 50 mounted. The rear end of the supporting arm 44 extends in a horizontal direction from the top of the rear end of the body 1 while the forward portion 45 of said supporting arm 44 is arched and then secured

to the top of the body 1 in a suitable manner, as shown at 46. The point 47 of the supporting arm 44 at the connection of the main or horizontal portion with the arched portion thereof rests upon the rear end of 70 the top of the body 1, as will be readily understood by referring to Figs. 1 and 3 of the drawings. A suitable bracing or strap member 48 is engaged around the downwardly curved portion of the supporting arm 44 and is secured by its opposite ends to the top of the body 1.

In order to lock the set screw 43 in adjusted position and regulating the tension of the arcuate spring 37, I provided the head 80 of the set screw 43 with peripheral ratchet teeth 49 with which is adapted to be engaged the upstanding working edge 50 of a locking plate 51 which is adjustably mounted upon the horizontal rear end of the supporting arm 44 by means of a set screw 52 engaged through an elongated longitudinal slot 53 of said locking plate 51 and a thumb nut 54 threaded upon said set screw 52. It will be readily seen that after the set screw 90 43 has been adjusted and the upstanding working edge 50 of the adjustable locking plate 51 engaged with the teeth 49, the thumb nut 54 may be turned into binding engagement with the upper face of said 95 locking plate 51 to retain the latter in proper position.

By referring to Fig. 6, it will be seen that each bracket 33 is formed in such manner as to support a pair of forward and rear rollers 32, thereby assuring a more even pressure upon the block 20.

By referring to Figs. 1, 2 and 3, it will be seen that the body 1 is provided with a door 55 at its forward end and which door, 105 when closed, forms the forward portion of the top of the body 1, being hinged to the remainder of said top by suitable hinges 56. The door 55 is provided in order that the operator may release the forward axle 4 and the crank shaft 14 and parts carried by said shaft 4 and crank shaft 14 to oil the same or for any other purpose desired without inverting the complete machine. When the door 55 is in closed position, it may be securely locked by engagement of the apertured free end 57 of the leaf spring 58 with the pin 59 projecting from the forward edge of said door 55. It will be understood that the opposite end 60 of the 110 spring 58 is secured to the front of the body 1 and the central portion of said leaf spring 58 is bowed outwardly, in order that the spring may serve to securely lock the door 55 in closed position.

From the foregoing it will be apparent that the machine will be automatic in operation and highly efficient in use, as the pressure upon the block 20 may be readily regulated and the block 20 with its sand 120

paper sheet 21 will be properly guided at all times.

While the preferred embodiment of the invention has been shown and described, it will be understood that minor changes in the details of construction, and arrangement of parts may be made within the scope of the appended claims without departing from the spirit of the invention or sacrificing any of the advantages of the same.

I claim:

1. A sand papering machine comprising a wheeled member, guide members mounted upon said wheeled member, a sand paper carrying block mounted for movement upon said guide members, means by which the wheeled member may be drawn over a surface to be treated, means for causing a reciprocating movement of said block upon movement of the first-mentioned member over said surface to be treated, and pressure exerting means carried by said first-mentioned member to retain said block in proper position with respect to the surface to be treated.

2. A sand papering machine comprising a wheeled member, a movable member, guide members mounted upon said movable member, a block, means for securing a surface treating member to said block, guide sleeves mounted upon said block, said guide members being engaged in said guide sleeves, means for causing reciprocating movement of said block upon movement of the movable member, and means carried by said movable member for exerting a pressure upon the upper face of said block.

3. A sand papering machine comprising a movable member, guide members carried by said movable member, a block mounted upon said guide members, means for causing reciprocating movement of said block upon said guide members during movement of said movable member, means for securing a surface treating member to said block, an arm mounted upon said movable member, adjustable pressure regulating means carried by said arm for exerting a pressure upon said block, and means for locking the pressure exerting means in adjusted position.

4. A sand-papering machine comprising a wheeled member, a movable member, and guide members mounted upon said movable member, a movable block, a surface-treating member, means for securing said surface-treating member to said block, means for inclosing and supporting said guide members, said guide members being connected with said block, means for reciprocating said movable member, and means carried by said movable member for exerting a pressure upon the upper face of said block.

5. A sand-papering machine comprising a movable member, guide members carried by

said movable members, a block mounted upon said guide members, means for reciprocating said block upon said guide members, means for securing a surface-treating member to said block, and adjustable pressure-exerting means carried by said movable member and engaged with said block.

6. A sand-papering machine, comprising a movable member, and reciprocable block slidably supported by the movable member, means carried by said movable member for imparting a reciprocatory movement to said block upon movement of the former, a surface treating element mounted upon said block, a supporting arm projecting over said block and mounted upon the movable member, a carriage mounted upon the block and carried by the arm, and means for exerting a pressure upon said carriage, said means being carried by carriage and engaged with said supporting arm.

7. A sand-papering machine comprising a movable member, a reciprocating block, means carried by said movable member for causing reciprocating movement of said block upon movement of said movable member, a surface-treating member mounted upon said block, a supporting arm projecting over the said block and mounted upon said movable member, a carriage mounted upon said block and carried by said arm, means for guiding said block, and adjustable pressure-regulating means carried by said arm and engaged with said carriage.

8. A sand-papering machine, comprising a movable member, a reciprocable abrasive block slidably supported by the movable member, means arranged upon said movable member for imparting a reciprocatory motion to the block upon movement of the former, an immovable arm carried by the movable member and projecting beyond the same, and adjustable pressure exerting means carried by said arm and engaged with said block for yieldably holding the latter in contact with the surface to be smoothed.

9. A sand-papering machine, comprising a movable member, a reciprocable abrasive block slidably supported by a movable member, a pitman connected to said movable member and said block for imparting a reciprocatory motion to the block upon movement of the movable member, an immovable arm carried by the movable member and projecting beyond the same, and adjustable pressure exerting means carried by said arm and engaged with said block for yieldably holding the latter in contact with the surface to be smoothed.

10. A sand-papering machine, comprising a wheel supporting frame, a reciprocable abrasive block slidably supported by the frame, a pitman connected to one wheel of the frame and to said block for imparting a reciprocatory movement to the block upon

1,195,428

movement of the frame, an immovable arm
carried by the frame and projecting beyond
the same, and adjustable pressure exerting
means carried by said arm and engaged with
5 said block for yieldably holding the latter
in contact with the surface to be smoothed.

In testimony whereof I affix my signature
in presence of two witnesses.

BERT W. WILLIAMS.
